UNITED STATES PATENT OFFICE

FRANCIS N. WOODMAN, OF CLINTON, MASSACHUSETTS, ASSIGNOR TO WICKWIRE
SPENCER STEEL COMPANY, OF NEW YORK, N. Y., A CORPORATION OF DELAWARE

SPIRAL CONVEYER BELT

Application filed December 12, 1928. Serial No. 325,601.

This application is a continuation in part of my prior application Serial No. 271,323 and the invention relates to a conveyer belt formed of interlaced spiral wire members.

5 When such belts or conveyers are operated under excessive tension, and particularly when exposed at the same time to relatively high temperatures, there is a marked tendency to stretch the conveyer and at the same 10 time to reduce the width.

It is one object of my invention to provide means for maintaining such a conveyer belt at substantially full width, even under adverse operating conditions.

15 To the attainment of this object in the preferred form, I provide compression-resisting elements in and between certain of the spiral wire members, so disposed relative thereto as to effectually prevent substantial contraction 20 of the conveyer transversely or widthwise thereof. If the belt is thus held from transverse shrinkage, lengthwise stretching of the belt is also substantially eliminated.

25 A further object of the invention is to provide a conveyer belt in which the spiral members are formed of a highly heat-resistant alloy, by which provision the utility of the belt is greatly increased and its field of application extended, as will be hereinafter explained.

Preferred forms of the invention are shown in the drawings in which

35 Fig. 1 is a plan view of a portion of a conveyer belt embodying my improvements;

Fig. 2 is an enlarged sectional end elevation, taken along the line 2—2 of Fig. 1;

Fig. 3 is an enlarged detail end view, looking in the direction of the arrow 3 in Fig. 1;

40 Fig. 4 is a view similar to Fig. 1, but showing a modified construction; and

Fig. 5 is a diagrammatic view illustrating a novel use of my improved belt.

Referring particularly to Figs. 1 to 3, my 45 improved belt comprises a series of wire members 10 which are wound in spiral form and are interlaced with adjacent spiral members as shown. After the spiral members are thus interlaced, the thickness of the belt 50 may be reduced by passing the belt between

pressure rolls effective to more or less flatten the round spirals, as indicated in Fig. 3.

In order to prevent widthwise contraction or shrinkage of the belt, I place shrinkage resisting members or rods 12 in and between certain adjacent spiral wires 10, as indicated in Figs. 1 and 2. The selvage ends of successive pairs of said adjacent wires are then bent and looped together, as shown in Figs. 1 and 3, thus providing a smoother edge for the belt and also presenting a barrier at each edge of the belt, effective to prevent longitudinal displacement of the rods 12.

It will be understood that the rods 12 are inserted at selected intervals along the belt, 65 varying with the conditions of operation. In some cases the rods may be quite close together, whereas in other cases a rod once in six or eight or even ten inches may be sufficient.

70 When excessive tension is placed on a wire conveyer belt, there is a tendency to elongate or stretch the belt, which induces a corresponding shrinkage widthwise. The rods 12 effectively prevent such transverse shrinkage 75 by reason of their close frictional engagement with the coils of the spiral wire members. Furthermore, belt shrinkage can only occur by bending or buckling the rods 12 and this is effectively prevented by the fact that each 80 rod 12 is closely engaged on each side by the successive spirals of adjacent wires 10.

While it is desirable to bend the ends of the spiral wires 10 to abut the ends of the rods 12, this is not indispensable, as the advantage 85 described may be to a large extent attained in the construction shown in Fig. 4, in which the bent ends of the spiral members do not abut the rods 12. It is found that the heavy tension on the spiral members when in use 90 causes them to bite into the rods 12 and form close frictional contact therewith, so that slipping of the spiral coils along the rods is effectively prevented, even without the abutting bent ends.

95 In either form of the construction, the rods 12 also fit closely into the curves of the spiral members and prevent a considerable part of the initial elongation which otherwise occurs when directly adjacent spirals are placed un- 100

der strain. Such strain causes the spiral coils to bend more sharply about each other, elongating the belt, but in my construction this sharp bending is largely avoided by the close fit of the rods between the coils.

It has heretofore been considered impossible, or at least impractical, to use spiral wire conveyer belts in furnaces or in other places where they are exposed to high temperatures. When exposed to such high temperatures, the longitudinal stretching and transverse shrinkage of the belts is greatly increased and it was found impossible to maintain a belt in anything like its original dimensions. I find, however, that by constructing a belt out of wire drawn from a special high temperature heat-resisting alloy and particularly by utilizing my shrinkage-resisting cross bars in a belt formed from such wire, that a conveyer belt may be produced which may be effectively used for conveying articles through an annealing or heat-treating furnace or for other purposes where high temperatures are encountered.

While I do not wish to be limited to the use of a specific alloy, the following composition has been found suitable for belts exposed to a range of temperature up to 1600° F.

Carbon	.16 to .24%
Chromium	17 to 18%
Nickel	25 to 26%
Silicon	2 to 3%
Iron	55.84 to 52.76%

Such a special alloy, heat-resisting belt possesses many advantages over the conveyer devices now in use for high temperature work, and these advantages are increased by using my shrinkage-resisting rods in such a belt.

My improved belt has a very low thermal capacity and consequently lends itself to heat economy. The belt has a substantially continuous unbroken smooth surface and is substantially free from vibration, as compared with belts formed of linked plates and other similar structures. This is of particular importance in enameling jewelry in silver-smith work, and in any other operation where vibration may disturb the relative position of the parts or elements thereof.

My improved belt is easily spliced and is continuous after splicing, there being no projection or difference in thickness at the point where the splice is made. The belt does not warp or crack as has been the case with sheet metal link belts and the natural flexibility of the belt permits it to run smoothly over relatively small rollers or pulleys if necessary.

The belt may be readily produced in any desired width or length, and the two sides of the belt are commonly identical, so that the belt may be reversed and the wear on the belt may thus be evenly distributed.

It may also be readily adapted to a positive drive by inserting spaced additional coils at one side thereof as disclosed in my prior application Serial No. 266,059, filed by me March 30, 1928.

While certain of the advantages of my improved belt may be attained by using a belt of ordinary material provided with shrinkage-resisting cross rods, and other advantages may be obtained by using a belt without cross rods but formed from special heat-resistant wire, the full advantages of the invention are attained by a combination of these two features and by such combination a belt is produced which is available for use under conditions heretofore considered impossible for wire belts.

In Fig. 5, I have indicated my improved belt B in use for conveying material or articles of manufacture through an annealing or enameling or heat-treating furnace F, in which combination the advantages enumerated may be fully attained.

Having thus described my invention and the advantages thereof, I do not wish to be limited to the details herein disclosed, otherwise than as set forth in the claims, but what I claim is:—

1. A wire conveyer belt effective to transport articles or products of substantial weight and comprising a series of interlaced spiral wire members, a series of cross rods extending transversely of said belt, each of said rods being positioned in and between the spaced turns of two adjacent interlaced spiral wire members, whereby substantial change in width of said belt is effectively prevented, and means for holding the rods and wires against relative lateral displacement, in either direction transversely of the belt.

2. A wire conveyer belt effective to transport articles or products of substantial weight and comprising a series of interlaced spiral wire members, and a plurality of compression-resisting cross rods inserted in and between the coils of certain of said spiral wire members and relatively closely spaced longitudinally of said conveyer belt, whereby substantial transverse shrinkage of said belt is effectively prevented, said cross rods being retained against endwise movement transversely of said conveyer belt by abutting edge portions of said belt.

3. A wire conveyer belt effective to transport articles or products of substantial weight and comprising a series of interlaced spiral wire members bent and looped together in successive pairs at the edges of said belt, and shrinkage-resisting cross rods loosely inserted in and between the overlapping portions of certain of said joined pairs of spiral wire members and engaging at their ends with the bent and looped ends of said spiral wire members, whereby displacement of said cross

rods and substantial transverse contraction of said conveyer belt is effectively prevented.

4. A wire conveyer belt effective to transport articles or products of substantial weight during heat treatment thereof at high temperatures, said belt comprising a series of interlaced spiral wire members formed of a highly heat resistant metal, and a series of cross rods extending transversely of said belt and held from endwise displacement therein, each of said rods being positioned in and between the turns of two adjacent interlaced spiral wire members, and means for holding the rods and wires against relative displacement in either direction, said cross rods frictionally engaging the coils of said spiral wire members, whereby movement of the spiral coils axially of said rods is prevented when said belt is under load tension.
5. A wire conveyer belt effective to transport articles or products of substantial weight during heat treatment thereof at high temperatures, said belt comprising a series of interlaced spiral wire members formed of highly heat resistant metal, said members being bent and looped together in successive pairs at the edges of said belt, and shrinkage-resisting cross rods loosely inserted in and between the overlapping coils of certain of said joined pairs of spiral members, whereby substantial transverse contraction of said conveyer is effectively prevented when under load tension, said rods being held from endwise displacement transversely of said belt by abutting the bent and looped ends of said spiral wire members.

In testimony whereof I have hereunto affixed my signature.

FRANCIS N. WOODMAN.
